G. A. Mansfield

UNITED STATES PATENT OFFICE.

GEORGE A. MANSFIELD, OF BOSTON, MASSACHUSETTS.

IMPROVEMENT IN BOOTS AND SHOES.

Specification forming part of Letters Patent No. 33,396, dated October 1, 1861.

To all whom it may concern.

Be it known that I, GEORGE A. MANSFIELD, boot and shoe dealer, of Boston, county of Suffolk, and State of Massachusetts, have invented certain new and useful Improvements in the Manufacture of Boots and Shoes; and I hereby declare that the following description, with the accompanying drawings, forms a full, clear, and exact specification thereof.

My invention and improvement consists in the introduction of an intermediate metallic sole or part sole between the outer and inner soles of the boot or shoe for the purpose of preventing dampness from reaching the foot through the sole, and increasing the stability and durability of the boot or shoe. I also form at the toe or anterior part of the sole or part sole a metallic welt, which I term the "toe-guard," as it effectually prevents wearing or "stubbing out the toe," as it is termed, said welt or toe-guard extending across the toe and for a short distance more or less down the side of the boot or shoe.

The accompanying drawings represent my improvements.

Similar letters represent similar parts in all the views.

Figure 1 is a side elevation of a shoe with my intermediate metallic sole and toe-guard. Fig. 2 is a longitudinal vertical section of said shoe. Fig. 3 is an independent top view of the intermediate metallic sole with the toe-guard formed thereon.

In the drawings, *a* represents the outer sole; *b*, the inner sole; *c*, the intermediate metallic sole or part sole; *d*, the metallic welt or toe-guard. It may be observed that I usually form the toe-guard by rolling or folding a portion of the metallic sole over a piece of metallic wire *e*, as shown in section in Fig. 2, though this toe-guard or welt can be formed by rolling or folding a portion of the metallic sole over itself one, two, three, or more times,

as shown at *f* in the sectional detail, Fig. 4, or by soldering on a separate piece of metal, as shown at *g* in the sectional detail, Fig. 5.

In construction I first last the boot or shoe by placing the inner sole on the last and drawing the edges of the vamp over it in the usual manner. I then place upon it in proper position the intermediate metallic sole or part sole formed either with or without the welted protecting toe-guard, and then place over all the outer sole, and fasten by one or more rows of nails or pins driven through all three of the soles, or if it is desired to make a sewed boot or shoe the metallic sole can be cut a little smaller all around than the outer sole, and thus admit of the outer sole being stitched outside the metallic sole to an independent welt in the usual manner of making sewed shoes.

I do not claim the introduction of an intermediate metallic sole between the ordinary outer and inner soles of a boot or shoe for the purpose of preventing the transmission of cold and dampness, as that principle is already secured to William J. Lyman by a patent granted June 7, 1859; but

I claim—

The metallic guard or welt constructed substantially as herein described, and extending either completely around the boot or shoe or being used only at the toe or such other parts as may be liable to uncommon external wear and abrasion, said guard or welt being applied either to the outer edge of one of said Lyman's metallic insoles or independently of the principle of his invention merely extending inward a sufficient distance to receive the pegging, sewing, or nailing.

GEO. A. MANSFIELD.
